(57) **CLAIM**

The ornamental design for a breath detector, as shown and described.

DESCRIPTION

FIG. 1 is a front perspective view of a breath detector showing our new design;

FIG. 2 is a rear perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof;

FIG. 8 is a right side view thereof; and,

FIG. 9 is a right side view thereof in a second position. FIG. 9 includes CAD lines that represent contour and not surface decoration.

1 Claim, 9 Drawing Sheets
